POWER TRANSMISSION

James Robinson, Detroit, Mich., assignor to
 Vickers Incorporated, Detroit, Mich., a corporation of Michigan

Application December 16, 1940, Serial No. 370,364

5 Claims. (Cl. 242—75)

This invention relates to power transmissions, particularly to those of the type comprising two or more fluid pressure energy translating devices, one of which may function as a pump and another as a fluid motor.

The invention is more particularly concerned with a hydraulic power transmission system adapted for use with a strip material handling device of the type where the strip material is passed back and forth between two reels and is alternately uncoiled from the first reel and recoiled onto the second reel and then uncoiled from the second reel and recoiled onto the first reel during the reverse movement of the strip. In the application of Ferris T. Harrington and James Robinson, Serial No. 357,896, there is disclosed a power transmission system particularly adapted for reeling strip material off from one reel and onto another. In the device there disclosed the operation is always in one direction, and it is impossible to utilize the system for machines of the type where the strip is coiled and uncoiled alternately in opposite directions.

It is an object of the present invention to provide a hydraulic power transmission system in which the power conserving advantages of the aforesaid copending application may be obtained with a strip material handling device operating alternately in either direction.

A further object is to provide improved pressure responsive regulating means for a variable displacement fluid pressure energy translating device wherein the action may be selectively reversed to either increase the displacement of the device with increases in pressure or to decrease the displacement of the device with increases in pressure.

Further objects and advantages of the present invention will be apparent from the following description, reference being had to the accompanying drawing wherein a preferred form of the present invention is clearly shown.

In the drawing:

Figure 1 is a diagrammatic view of a power transmission system incorporating a preferred form of the present invention.

Figure 2 is a sectional view of a pressure responsive regulating mechanism embodied in the circuit disclosed in Figure 1.

A sectional machine for operating on strip material is illustrated in the drawing and, by way of example, comprises a rolling stand 10 which constitutes a driving section. The details of the rolling stand form no part of the present

invention, it being understood that many other mechanisms for operating on strip stock and at the same time moving it longitudinally from right to left or from left to right could equally well form the driving section of the machine.

A supply reel is indicated at 12 comprising a coil of strip 14 which, as disclosed, is partly unwound so that a flat section of strip 16 extends through the driving section 10 to a take-up reel 18 where the strip is again reeled into a coil 20.

The roll stand 10 has a drive shaft 22 which is driven by means of a reversible drive gearing 24 from an electric motor 26. The reversible gearing 24 has a shift lever 28 which may be operated by means of a piston 30 reciprocable within a cylinder 32. Thus, when pressure is applied to the lower end of the cylinder 32, the lever 28 will be shifted clockwise to reverse the gearing 24.

Each of the reels 12 and 18 is adapted to be selectively driven by or to drive one of a pair of hydraulic displacement devices 34 and 36, each of which is adapted to function either as a pump or as a motor. The devices 34 and 36 are of the variable displacement type and, as illustrated in the drawing, may have a swinging yoke 38 and 40, respectively, the angular position of which determines the stroke or displacement of the device. Pumps and motors of this class are well known in the art such, for example, as illustrated in Thoma Patent No. 1,931,969. The devices 34 and 36 are each provided with a pressure responsive displacement regulator 42 and 44, respectively, the details of which are shown more clearly in Figure 2.

Connected in driving relation with the electric motor 26 is a second pair of hydraulic displacement devices 46 and 48 which may be similar to the devices 34 and 36 with the exception that they are not provided with pressure responsive displacement regulators. They may be provided, however, with manual controls 50 and 52 for altering their displacement from time to time to

provide for the use of reels of greater or lesser core diameter. In the circuit shown, and later to be described, the device 46 is so connected as to always act as a fluid motor and to assist the electric motor 26 in driving the roll stand 10. The device 48, however, is so connected as to always operate as a pump and so absorb power from the electric motor 26, or from the fluid motor 46.

The devices 34 and 36 are connected by conduits 54 and 56 with the end and center ports, 58 and 60, respectively, of the cylinder 32.

respectively, of a conventional pilot-operated, four-way, reversing valve 58. The two intermediate ports of the valve are connected by conduits 60 and 62 with the devices 46 and 48, respectively. Interposed in the conduits 60 and 62 are a pair of back pressure valves 64 and 66 of similar construction and arranged to block flow through their respective conduits except when a predetermined pressure has been reached in the conduit on one side of the valve.

The valves shown in the drawing are similar to that shown in Herman Patent No. 2,200,824, although it will be understood that any other suitable type of back pressure valve may be utilized at this point in the circuit. Since the flow in conduit 60 is always from the top to the bottom of the page and the flow in conduit 62 is in the opposite direction, the valves are positioned in the conduits in reverse relation so that valve 64 will open in response to pressure developed in the upper part of conduit 60 while valve 66 will open in response to pressure developed in the lower part of conduit 62.

Also interposed in conduit 62 is a relief valve 38 which may be similar to that illustrated in Vickers Patent No. 2,043,453, and serves to limit the maximum pressure against which the unit 48 must pump. The valve 38 also serves as a starting and stopping control by means of a pilot venting connection 70 leading from the control chamber of the valve 38. The connection 70 leads to a two-way pilot valve 72 for the purpose of selectively blocking or opening a connection to tank through conduits 74 and 76. The conduit 76 also communicates with one side of the hydraulic displacement unit 36 while a corresponding conduit 78 communicates with one side of the unit 34. Similarly the units 46 and 48 are provided with tank conduits 80 and 82.

It will be seen that the hydraulic units and circuit thus far described constitute a coupling circuit between the reel 12 and the reel 18 with a synchronizing connection to the roll stand 10. Thus, assuming the strip 16 to be moving in the direction of the arrows, unit 34 will be operated as a pump withdrawing oil from the tank through conduit 78 and delivering it through conduit 84, valve 58 and conduit 60 to the unit 48 driving the latter as a motor and discharging the oil to the tank 18 through conduit 80. Thus, depending upon the relative displacements of units 34 and 48, the reel 12 will be coupled to the motor 28 which in turn is mechanically coupled to the roll stand 10. Correspondingly, unit 48 will be driven as a pump by the motor 28, withdrawing fluid from the tank through conduit 82 and delivering it through conduit 62, valve 38 and conduit 80 to the unit 36 which acts as a motor to drive the reel 18. Oil discharged by the motor 36 returns to tank through the conduit 76. Thus the reel 18 is likewise coupled to the roll stand 10 at a speed ratio depending upon the relative displacements of units 48 and 36.

If the valve 58 be shifted by mechanism later to be described and the direction of roll stand 10 be reversed, the strip 16 will move in the opposite direction unwinding stock from reel 18 causing unit 36 to be driven as a pump delivering fluid through conduit 80, valve 58 and conduit 60 to the fluid motor 48. Likewise, the unit 48, still operating as a pump, will deliver fluid through conduit 62, valve 38 and conduit 82 into the unit 34, driving the latter as a motor and thus operating reel 12 to rewind the strip into coil 14.

During operation in either direction, the valve

64 in conduit 60 acts to maintain a predetermined back pressure on whichever of the units 34 and 36 is operating as a pump and thus insures against overrunning or coasting. Similarly, the valve 66 imposes a predetermined back pressure in the conduit 62 between it and the pump unit 48 for the purpose of maintaining a supply of pilot pressure available at the branch conduit 34 which is always in communication with the bottom portion of conduit 62.

Conduit 34 delivers this pilot fluid to the pressure port of a conventional rotary four-way pilot valve 86, the tank port of which is connected to the tank by a conduit 88. The valve 86 in the position shown connects pilot pressure conduit 84 with a conduit 90 and connects the tank conduit 88 with a conduit 92. When the valve is shifted forty-five degrees clockwise, pilot pressure is connected to conduit 92 while conduit 90 is connected to tank. The conduits 90 and 92 provide parallel pilot connections, first, to the opposite ends of cylinder 32, and then to the pilot operating chamber of the valve 58 as well as to the pilot operating chambers of a pair of pilot-operated four-way valves 94 and 96 which serve to control the action of displacement regulators 42 and 44. These conduits also connect with certain chambers 98 and 100 in each of the displacement regulators 42 and 44.

30 Thus, with the valve 86 in the position shown in the drawing, pilot pressure in conduit 90 holds piston 30 down, holds valve 58 to the left and holds valves 94 and 96 to the right and maintains pressure in the chamber 98 of regulator 42 35 and in the chamber 100 of regulator 44. When the valve 86 is shifted to its opposite position, exactly opposite conditions are set up in each of the parts mentioned.

Referring now to Figure 2, the section of the 40 regulator 44 is there illustrated on a larger scale, and, since the the regulator 42 is identical, the construction of only one will be described. Thus the regulator comprises a cylindrical body 102 having an enlarged bore 104, the opposite ends 45 of which form the chambers 98 and 100. At its left portion the body 102 is provided with a smaller bore 106 in which a balanced piston 108 is reciprocably mounted. The latter carries a rod 110 projecting through the left end of the body 102 and which is connected by means of a link 112 with the swinging yoke 40 of unit 36. At its righthand side the piston 108 has a corresponding rod 114 which is provided with a portion 116 of reduced diameter. At its righthand end the 55 rod 114 is provided with a portion 118 of normal diameter and which may be formed as a separate piece and assembled to the main portion of rod 114 as by threading thereon and which is slidable in a small bore 120 in an end cap 122 which 60 closes the righthand end of bore 104. A small end cap 124 closes the end of bore 120 and may be provided with a breather hole 126. Mounted against the shoulders at the opposite ends of the reduced portion 116 are a pair of washers 128 65 and 130 forming abutments for a compression spring 132.

Slidable in the bore 104 is a spring abutment shifting member 134 formed as a differential piston and having a reduced portion 136 slidable 70 in the bore 106. The member 134 has a cylindrical recess 138 at its righthand end within which the spring 132 and washers 128 and 130 are mounted. An end cap 140 is removably secured to the righthand face of the member 134 to close the open end of the recess 138. The member

134 is shifted and maintained in the position illustrated by pilot pressure admitted to chamber 98. When pilot pressure is admitted to chamber 98, the member 134 shifts to the right until the end cap 140 abuts against the end cap 122.

The piston 108 divides the bore 106 into two chambers 142 and 144 which connect by conduits 146 and 148 with the intermediate ports of four-way valve 96. A restricted passage 150 forms a bypass between chambers 142 and 144 capable of carrying a limited flow of fluid.

Referring now again to Figure 1, the central ports of valves 94 and 96 are connected by conduits 152 and 154 with the conduits 54 and 56, respectively. The end ports of these valves are connected by conduits 156 and 158 with small spring-loaded ball valves 160 and 162 which act as pilot relief valves opening in response to a predetermined pressure which depends upon the setting of the adjustable spring therein. The discharge side of the valves 160 and 162 is connected to tank by conduits 164 and 166.

The parts are shown in the drawing in the condition when the device is in operation with motor 26 running and with the roll stand 10 pulling the strip 16 from right to left in the direction of the arrows. The flow of fluid in the main coupling circuit is as previously described, and the pressure in the pilot circuit is maintaining all of the pilot control members in the position shown in the drawing. The adjusted position of the stroke varying yokes of the units 46 and 48 remains fixed as determined by the original diameter of the reel cores, while the stroke position of the yokes 38 and 40 is determined by the pressure conditions in conduits 54 and 56 due to the action of the regulators 42 and 44, respectively.

With the spring abutment shifting member 134 of regulator 42 shifted to its lefthand position, as illustrated, and with the valve 94 in its righthand position, it will be seen that the fluid pressure generated in line 54 by unit 34 is transmitted through conduit 152 to conduit 146 and accordingly acts on the lefthand face of the piston 108 of regulator 42. Due to the greater area over which member 134 is exposed to the pressure in chamber 98, the member 134 remains stationary regardless of the pressure developed in chamber 142. It will be seen that the pump delivery pressure on the lefthand face of piston 108 acts in a direction tending to reduce the displacement of unit 34 and also that the spring 132 will be compressed by spring washer 130 which moves to the right with piston rod portion 118 whenever piston 108 moves to the right. Thus the spring 132 biases the piston 108 and yoke 38 to the left against the pressure in the chamber 142. The line pressure is, however, also transmitted to the chamber 144 on the righthand side of the piston 108 through the restricted passage 150, and, so long as the relief valve 160 remains closed, the pressures on opposite sides of piston 108 will balance in opposition to one another, leaving the spring 132 to maintain the yoke 38 in its full displacement position.

When, however, the line pressure rises above the setting of valve 160, the latter will open, and a point will be reached where it will pass more oil to the tank out of chamber 144 than can flow into chamber 144 through the restricted passage 150. Accordingly, piston 108 will move to the right reducing the displacement of unit 34 until the pressure in line 54 drops to the point where 75

relief valve 160 again closes or at least closes sufficiently to pass no more oil than passes through conduit 150. Thus, as the pressure in conduit 54 tends to rise, the stroke or displacement of unit 34 is correspondingly reduced.

Since the unit 46 is driven at constant speed by the motor 26 and since its displacement is fixed, the unit 34 will have to turn at a higher speed as its stroke is progressively decreased in order to pass the same quantity of fluid as before. Consequently the speed of reel 12 is progressively increased as is necessary from the fact that its diameter is decreasing by reason of progressive layers of strip being unwound therefrom while the lineal speed of the strip is maintained constant by the roll stand 10. The progressive decrease of displacement or stroke at unit 34 also acts to decrease the torque reaction which is maintained by unit 34 on the reel 12 which also is necessary due to the decreasing diameter of the coil 14 while the tension in strip 16 is maintained constant.

It is an inherent characteristic of any variable displacement hydraulic unit that, when acting as a pump against a fixed delivery pressure, the torque required to drive the pump decreases progressively with decreases in displacement. This decrease in torque and the previously mentioned increase in speed of the unit 34 and reel 12 is a hyperbolic relationship so that the product of torque and speed remains constant as is fully explained in the aforesaid copending application of Harrington and Robinson.

It will be noted that the work done in unwinding strip from the coil 14 against a constant back tension is restored to the system at motor 26 instead of being wasted in the form of heat as would be the case if the usual friction brake were applied to the supply reel shaft 12.

40 At the same time that the above-described action is occurring at the supply reel 12, the take-up reel 18 is being driven by the unit 36 acting as a motor. In this case, however, the spring abutment shifting member 134 has been shifted to its opposite position so that the line pressure acting in chamber 144 tends to increase the displacement or stroke of the member 36. Thus, as the pressure in conduit 56 tends to rise due to the progressively increasing diameter of coil 20, yoke member 40 will be progressively shifted to the right. This has the effect of correspondingly reducing the speed at which reel 18 is driven by the fixed displacement pump 48 and, at the same time, progressively increases the torque applied by the unit 36 to the reel 18. Thus, the action of unit 36 in driving the reel is regulated to correspond to the requirements of the progressively increasing coil diameter at 20, while maintaining constant tension in the strip section 16 between coil 20 and roll stand 10 and while also maintaining constant linear speed of the strip.

It may be observed that, neglecting losses in the system, the power required to drive pump 48 is equal to the power delivered by motor 46 so that the only work necessary for motor 26 to do is to make up the losses in the reel coupling hydraulic system and to supply the power required to operate roll stand 10. When the length of strip has been fully unwound from coil 14 and fully wound onto coil 20, the pilot valve 86 may be shifted to reverse the pilot connections, shifting the piston 38 to reverse the direction of drive at roll stand 10 and also shifting the three pilot-operated valves 56, 94 and 96 as well as the two spring abutment shifting mem-

bers 134 of the two stroke regulators. The action under these conditions is exactly corresponding to that previously described except that the direction of strip movement is reversed and the unit 34 now acts as a hydraulic motor driven by the pump 48 while the unit 36 acts as a pump to drive the fluid motor 46.

While the form of embodiment of the invention as herein disclosed constitutes a preferred form, it is to be understood that other forms might be adopted, all coming within the scope of the claims which follow.

What is claimed is as follows:

1. In a strip material handling device comprising a pair of reels each adapted to alternately act as a supply reel or a take-up reel as the strip is passed back and forth between the reels, a pair of constant pressure, variable volume, hydraulic displacement devices, one connected in driving relation to each reel, constant volume, variable pressure, hydraulic displacement means driven at a speed proportional to the linear speed of the strip, a circuit connecting said displacement means to receive and deliver all of the fluid passing through each constant pressure displacement device, and means for reversing the direction of strip motion.

2. In a strip material handling device comprising a pair of reels each adapted to alternately act as a supply reel or a take-up reel as the strip is passed back and forth between the reels, a pair of constant pressure, variable volume, hydraulic displacement devices, each device having a pressure responsive volume regulator, one connected in driving relation to each reel, constant volume, variable pressure, hydraulic displacement means driven at a speed proportional to the linear speed of the strip, a circuit connecting said displacement means to receive and deliver all of the fluid passing through each constant pressure displacement device, and means for reversing the direction of strip motion and simultaneously reversing the action of both volume regulators.

3. A strip material handling device comprising a supply reel from which the strip is to be unwound and a take-up reel onto which the same strip is to be wound, a pair of constant pressure, variable volume, hydraulic displacement devices, one connected in driving relation to each reel, a pair of constant volume, variable pressure, hydraulic displacement devices, means for driving the last-mentioned devices at a controlled speed, and fluid supply and return conduits connecting each constant pressure device with a separate one of the constant volume devices.

4. In a sectional machine for operating on strip material the combination of a driving section having means for engaging the strip and moving it longitudinally, power means for driving the driving section at a controlled speed, a supply reel section from which the strip is unreeled by the pull of the driving section, a take-up reel section onto which the strip is reeled after leaving the driving section, and means for controlling the tension of the strip between said three sections comprising variable displacement fluid pressure energy translating units, one coupled in driving relation to each reel section, hydraulic fluid pressure energy translating mechanism driven with the driving section, a hydraulic circuit connecting said units with said mechanism, pressure responsive means for regulating the displacement of each of said units, means for reversing the driving section to cause the strip to pass from the take-up section to the supply section, and means for reversing the action of said pressure responsive means whereby each unit will be regulated to increase its displacement with increases in pressure during winding operation and to decrease its displacement with increases in pressure during unwinding operation.

5. In a sectional machine for operating on strip material the combination of a driving section having means for engaging the strip and moving it longitudinally, power means for driving the driving section at a controlled speed, a supply reel section from which the strip is unreeled by the pull of the driving section, a take-up reel section onto which the strip is reeled after leaving the driving section, and means for controlling the tension of the strip between said three sections comprising variable displacement fluid pressure energy translating units, one coupled in driving relation to each reel section, hydraulic fluid pressure energy translating mechanism driven with the driving section, a hydraulic circuit connecting said units with said mechanism, pressure responsive means for regulating the displacement of each of said units, means for reversing the driving section to cause the strip to pass from the take-up section to the supply section, means for reversing the action of said pressure responsive means whereby each unit will be regulated to increase its displacement with increases in pressure during winding operation and to decrease its displacement with increases in pressure during unwinding operation, and means for simultaneously actuating both said reversing means.
